(57) CLAIM

The ornamental design for an electrical power unit, as shown and described.

DESCRIPTION

FIG. 1 is a front perspective view of a first embodiment of the electrical power unit and showing our new design;

FIG. 2 is a rear perspective view thereof;

FIG. 3 is a front elevation thereof;

FIG. 4 is a rear elevation thereof;

FIG. 5 is a top plan view thereof;

FIG. 6 is a bottom plan view thereof;

FIG. 7 is a right side elevation thereof;

FIG. 8 is a left side elevation thereof;

FIG. 9 is a front perspective view of a second embodiment of the electrical power unit and showing our new design;

FIG. 10 is a rear perspective view thereof;

FIG. 11 is a front elevation thereof;

FIG. 12 is a rear elevation thereof;

FIG. 13 is a top plan view thereof;

FIG. 14 is a bottom plan view thereof;

FIG. 15 is a right side elevation thereof;

FIG. 16 is a left side elevation thereof;

FIG. 17 is a front perspective view of a third embodiment of the electrical power unit and showing our new design;

FIG. 18 is a rear perspective view thereof;

FIG. 19 is a front elevation thereof;

FIG. 20 is a rear elevation thereof;

FIG. 21 is a top plan view thereof;

FIG. 22 is a bottom plan view thereof;

FIG. 23 is a right side elevation thereof;

FIG. 24 is a left side elevation thereof;

FIG. 25 is a front perspective view of a fourth embodiment of the electrical power unit and showing our new design;

FIG. 26 is a rear perspective view thereof;

FIG. 27 is a front elevation thereof;

FIG. 28 is a rear elevation thereof;

FIG. 29 is a top plan view thereof;

FIG. 30 is a bottom plan view thereof;

FIG. 31 is a right side elevation thereof;

FIG. 32 is a left side elevation thereof;

FIG. 33 is a front perspective view of a fifth embodiment of the electrical power unit and showing our new design;

FIG. 34 is a rear perspective view thereof;

FIG. 35 is a front elevation thereof;

FIG. 36 is a rear elevation thereof;

FIG. 37 is a top plan view thereof;

FIG. 38 is a bottom plan view thereof;

FIG. 39 is a right side elevation thereof;

FIG. 40 is a left side elevation thereof;

FIG. 41 is a front perspective view of a sixth embodiment of the electrical power unit and showing our new design.

FIG. 42 is a rear perspective view thereof;

FIG. 43 is a front elevation thereof;

FIG. 44 is a rear elevation thereof;

FIG. 45 is a top plan view thereof;

FIG. 46 is a bottom plan view thereof;

FIG. 47 is a right side elevation thereof; and,

FIG. 48 is a left side elevation thereof.

In the drawings, the broken lines are for the purpose of illustrating environment only and form no part of the claimed design.
